United States Patent Office.

JOSEPH S. GODFREY, OF LESLIE, MICHIGAN.

Letters Patent No. 77,184, dated April 28, 1868.

IMPROVEMENT IN REVOLVING MOULD-BOARDS.

The Schedule referred to in these Letters Patent and making part of the same.

TO WHOM IT MAY CONCERN:

Be it known that I, JOSEPH S. GODFREY, of Leslie, in the county of Ingham, and State of Michigan, have invented a new and useful Revolving Mould-Board; and I do declare that the following is a true and accurate description thereof, reference being had to the accompanying drawings, and to the letters of reference marked thereon, and making a part of this specification.

The drawing is a perspective view of my invention.

A A are the revolving mould-boards. B B are the cutters, C C are the shares, D D are the shafts, E is the plough-frame.

The object of my invention is to render ploughing a much easier labor than when performed with any of the ploughs now in use, by saving the friction caused by the common mould-board.

In order to do this I construct a frame, E, in such a manner that I can attach as many of the ploughs as I may deem best for the various kinds of work to be done. To this frame I attach in any suitable manner one or more cutters, B B, with or without the shares C C. I then construct the concave mould-boards A A, which I hang upon the shafts D D. These shafts run in suitable boxes, attached to the frame E. These journals are set at such an angle as will allow the periphery of the revolving mould-board to run nearly upon a line with the face side of the cutters B B.

By the use of ploughs constructed as above described, I claim that the same amount of work can be accomplished with nearly one half less of power, while all friction and scouring of mould-boards are avoided.

I can use as many mould-boards and other parts, and attach as many ploughs to one frame as may be desired, and, by varying the size, the invention can be used as a cultivator as well as plough.

What I claim as my invention, and desire to secure by Letters Patent, is—

The combination of the mould-boards A A with the cutters B B, the shares C C, the shafts D D, and the frame E, when constructed substantially as described, for the purpose designed and set forth.

JOSEPH S. GODFREY.
